THERMIONIC AMPLIFIER

Bent Bülow Jacobsen and Alleman Holly Roche,
London, England, assignors to International
Standard Electric Corporation, New York, N. Y.

Application April 5, 1939, Serial No. 266,128
In Great Britain April 23, 1938

4 Claims. (Cl. 179—171)

This invention relates to thermionic amplifiers of the kind in which a portion of the output is fed back to the input in negative phase and more particularly to such amplifiers in which the phase of the feedback voltage on the control grid of the first valve has been upset by the connection to the control grid of an external circuit of large impedance.

According to the invention this objection is overcome by the application of feedback of substantially perfect phase shift to an electrode of the valve other than the control grid. Where the feedback is to a tetrode or pentode valve the feedback may be applied to both the control grid and the screen grid. In the case of a pentode both the signal input and the feedback voltage may also be applied to the suppressor grid.

The invention will be fully understood from the following detailed description and the accompanying drawing in which Figs. 1 and 2 are schematic diagrams of two embodiments of the invention.

Fig. 1 shows the circuit of an amplifier in which the feedback voltage is conveyed to the screen grid of a tetrode (or pentode) via the large condenser C_1 . In this circuit the valve V_1 has a voltage applied to its control grid from the generator G , its plate circuit being fed through the resistance R_1 . The resistance R_2 is used to apply the required steady voltage to the screen grid. The bias for the control grid is obtained from the usual biasing resistance R_3 shunted by the decoupling condenser C_3 . The load Z is fed through the condenser C_2 and the feedback voltage is taken from the output bridge consisting of the resistances R_5 , R_6 , R_7 and the plate cathode impedance of the valve. The resistance R_8 is included in the grid circuit of the valve and is the resistance across which the feedback voltage is generated.

In a normal amplifier when the generator G has a high internal impedance the effective feedback voltage on the control grid will generally differ in magnitude and phase from the feedback voltage on the resistance R_8 . This is due to the input capacity of the valve. The phase shift is particularly objectionable since it tends to render the amplifier unstable. If, for instance, the generator impedance is Z_1 ohms and the input impedance of the valve is Z_2 ohms, then the ratio of feedback volts on the grid of the valve to the feedback voltage on R_8 is

$$\frac{Z_2}{Z_1 + Z_2}$$

it being assumed that R_8 is small compared with Z_1 and Z_2 . Assume that the mutual conductance for the control grid is m_1 and for the screen grid is m_2 ; if the effect of the feedback is measured at the anode of V_1 then if the feedback is applied to the grid only, the relative feedback effect at the anode will be

$$\frac{m_1 \times Z_2}{Z_1 + Z_2}$$

If the feedback is applied to the screen only, the relative effect is then

$$\frac{m_2 \frac{R_2 Z_3}{R_2 + Z_3}}{\frac{R_2 Z_3}{R_2 + Z_3} + \frac{1}{\omega C_1}}$$

where Z_3 is the screen grid impedance and R_8 is again assumed to be small. If C_1 is made large then

$$\frac{1}{\omega C_1}$$

will be negligible at all relevant frequencies, and the relative feedback effect in the anode circuit will be m_2 . m_2 is purely scalar and the phase angle of the feedback is therefore in this case not affected by the input capacity of the valve. In the first case the same effect may be obtained by reducing Z_1 , the generator internal impedance, but this will be accompanied by decreasing gain and is therefore undesirable. In the second case there is no such decrease in gain.

In Fig. 1, however, feedback is applied to both the control grid and the screen grid, and the total feedback effect in the anode circuit is then the vectorial sum of the screen feedback and the control grid feedback. Since the screen grid feedback is of perfect phase shift the sum of the two feedbacks will be more correct in phase than would be the control feedback alone, the more so the larger the screen grid feedback. The reason for maintaining some feedback on the control grid is to increase the input impedance of the amplifier. Perfect phase shift means a phase shift of 180° with respect to the signal voltage applied to the control grid.

If the lead from the condenser C_1 to the resistance R_8 in Fig. 1 and also the lead from the generator G to the resistance R_8 are made slider contacts along the resistance, it will then be obvious that the relationship between the feedback on the control grid and the screen grid may be varied in any required manner. Thus, if desired, the feedback on the screen grid may be

made considerably greater than that on the control grid and this is the preferred condition, as under these circumstances the resultant phase shift of the feedback path will be more suitable.

Fig. 2 shows a further possible modification in which both feedback voltage and signal voltage are applied to the suppressor grid of a pentode as well as to the control grid, feedback voltage being also applied to the screen grid. The designations of the circuit elements in Fig. 2 are exactly the same as in Fig. 1, and no further description is therefore necessary.

What is claimed is:

1. An amplifier system comprising a tube having a cathode, an anode, a control grid and another grid, an input circuit of relatively high impedance connected between said control grid and said cathode, means for applying to said control grid through said input circuit a negative feedback voltage and means for applying to said other grid through a substantially negligible impedance a negative feedback voltage of substantially 180° phase shift with respect to the signal voltage applied to said control grid, whereby the stability of said amplifier is improved.

2. An amplifier according to claim 1 wherein

both of said feedback voltages are derived from the same source.

3. An amplifier system comprising a tube having a cathode, an anode, a control grid and a screen grid, an input circuit of relatively high impedance connected between said control grid and said cathode, a source of negative feedback voltage, means for applying through said input circuit a voltage derived from said source to said control grid to cause a feedback at a phase shift of other than 180° with respect to the signal voltage applied to said control grid and means for supplying through a substantially negligible impedance a voltage derived from said source to said screen grid to cause a feedback at a phase shift of substantially 180° with respect to the signal voltage applied to said control grid.

4. An amplifier according to claim 1, wherein said tube comprises a suppressor grid, further comprising means for connecting said input circuit to said suppressor grid, and means for applying a negative feedback voltage through said input circuit to said suppressor grid.
